UNITED STATES PATENT OFFICE.

CLARENCE W. TAYLOR, OF SIOUX CITY, IOWA.

INCANDESCENT GAS-BURNER.

SPECIFICATION forming part of Letters Patent No. 700,574, dated May 20, 1902.

Application filed March 19, 1902. Serial No. 99,001. (No model.)

To all whom it may concern:

Be it known that I, CLARENCE W. TAYLOR, a citizen of the United States, residing at Sioux City, in the county of Woodbury and State of Iowa, have invented new and useful Improvements in Incandescent Gas-Burners, of which the following is a specification.

This invention relates to certain new and useful improvements in incandescent gas-burners; and the object thereof is to construct a burner of this class in which the gas consumption, the incandescence of the mantle, and the mixing of the gas and air are thoroughly obtained.

15 A further object of the invention is to construct a burner of the class in which the escape of gas is prevented, the supply of gas easily regulated, and which is not sensitive to drafts.

20 The invention further aims to construct a burner of this class which shall be simple in its construction, strong, durable, efficient in its operation, and comparatively inexpensive to set up; and to this end the invention consists of the novel combination and arrangement of parts hereinafter more specifically described, illustrated in the accompanying drawings, and particularly pointed out in the claims hereunto appended.

25 30 In describing the invention in detail reference is had to the accompanying drawings, forming a part of this specification, wherein like numerals of reference indicate corresponding parts throughout the several views, and in which—

35 Figure 1 is a vertical central sectional view of my improved burner, showing the chimney, globe, and gallery in dotted lines. Fig. 2 is a plan view of the nipple with the gas-regulating plate mounted thereon. Fig. 3 is a similar view of a modified form of gas-regulating plate. Fig. 4 is a sectional elevation of a modified form of the burner and mixing tubes, and Fig. 5 is a section on the line 5 5

45 of Fig. 4.

Referring to the drawings by reference-numerals, 1 denotes a gas-supply pipe, to which is secured in any suitable manner the nipple 2, formed with an annular peripheral flange 3 near the bottom thereof and an annular peripheral shoulder 4 approximately centrally thereof. The top of the nipple 2 has secured

thereto in any suitable manner a diaphragm 5, provided with perforations or slots 6 for the passage of gas from the source of supply 55 through the nipple 2 to the burner-tube 7, the latter being of the ordinary Bunsen type, and which has its lower end surrounding the upper portion of the nipple 2 and resting upon the shoulder 4 of the latter. The tube 7 is secured to the nipple 2 in any suitable manner. The burner-tube 7 above the nipple 2 is provided with the usual air-inlets 8 and further provided below the inlets 8 with a slot 9 to permit of the operation of the gas-regulating plate, to be hereinafter referred to.

Mounted upon the top of the nipple 2 and within the burner-tube 7 below the air-inlets 8 is a gas-regulating plate 10, provided with a suitable opening or openings 11, adapted to 70 register with the openings or slots 6 in the diaphragm 5. The opening or openings 11 in the plate 10 is or are so arranged that one or more or all of the openings or slots 6 will be opened or closed when the plate 10 is rotated 75 upon the nipple 2 to bring the opening or openings 11 into or out of alignment with the openings or slots 6, thereby regulating the supply of gas to the burner. The plate 10 may be constructed without the opening or 80 openings, but of such shape that when rotated it will cause the opening or closing of one or more or all of the openings or slots 6 in the diaphragm 5. A construction of plate as referred to is shown in Fig. 2. By the adaptation of the plate in the manner set forth it will be obvious that the passage of gas can be 85 suitably regulated at will from the gas-supply to the burner. The plate 10 is constructed with an outwardly-projecting stud 12, which 90 extends through the slot 9 in the burner-tube 7. The stud 12 is provided so that the plate 10 can be rotated to regulate the passage of gas through the diaphragm, as before stated.

The reference-numeral 13 denotes an enlarged upper portion of the gas and air mixing tube and which forms the gas and air mixing chamber 14. The top of the enlarged portion 13 has mounted thereon a foraminous diaphragm 15, which projects over the edges 100 thereof and carries a heat-radiator 15' of any preferred form of construction, which depends downwardly into the chamber 14.

The reference-numeral 16 denotes the lower

portion of the gas and air mixing tube and is of much less diameter than the upper portion 13, but of a larger diameter than the burner-tube 7 and is also adapted to surround the 5 said burner-tube 7. The bottom of the lower portion 16 of the gas and air mixing tube is mounted upon the flange 3 of the nipple 2, and the portion 13 above the bottom thereof is provided with a series of air-inlets 17. The 10 lower portion 16 of the gas and air mixing tube is of such a diameter in relation to the burner-tube 7 that between them are formed the air-spaces 18. The gas and air mixing tube is retained in a uniform position in respect to the tube 7 by means of a series of studs 15 or beads 19, carried thereby and which engage the inner face of the gas and air mixing tube. These studs or beads extend in a vertical manner. The lower portion of the gas and air mixing tube is provided with an offset 20, forming a vertical groove 21, extending from the lower end of the said mixing-tube to slightly above the nipple 2, and is adapted to receive the stud 12 of the plate 10. The gas and air 20 mixing tube is loosely mounted upon the nipple 2, so it can be rotated at will, and owing to the stud 12 extending in the groove 21 the stud will be carried with the tube when rotated, and consequently impart a similar 25 movement to the plate 10 and regulate the passage or flow of the gas through the diaphragm 5, or, in other words, the plate 10 can be adjusted to any desired position by rotating the gas and air mixing tube, owing to its 30 engagement with the stud 12. The air is not only supplied to the interior of the burner-tube 7 through the openings 17 of the mixing-tube and the openings 8 of the burner-tube, but air is also supplied to the gas and air mixing chamber 14 through the medium of the 35 openings 17 and the air-spaces 18.

The reference-numeral 22 denotes a cylindrical cap which is mounted upon the diaphragm 15, the latter engaging the inner face 40 of the depending wall of the former. The cap is of such diameter in relation to the upper portion 13 of the gas and air mixing tube as to form an independent air-passage 23 between it and the mixing-tube. The top of the 45 cap is slotted or otherwise perforated, as at 24, to permit of the gas and air mixture from the chamber 14 and air from the passage 23 to enter within the mantle 25. The mantle is supported in a known manner and surrounds the cap 22, as shown. The gallery 50 26, chimney 27, and globe 28 are shown in dotted lines; but any preferred form of these devices may be employed.

In Fig. 4 of the drawings the burner-tube 7 is provided with an annular bead 29 above the air-inlets 30 for limiting the introduction of air to the burner-tube 7, as well as the mixing-chamber 14. The lower portion of the gas and air mixing tube may be provided with the 60 air-inlets 31 above the bead 29 of the burner-tube 7 for admitting air to the air-space 32 between the mixing and burner tubes. The

enlarged portion 33 of the gas and air mixing tube, which forms a mixing-chamber 14, may be corrugated or fluted, and an ordinary cap 70 34, with a slotted or perforated top 35, may be mounted upon the enlarged portion 33 and snugly fit the sides of the same, which dispenses with the projecting of the diaphragm and forms a series of independent air-passages 36. The reference-numeral 37 denotes the mantle, adapted to extend on the outside of the cap 34. The regulating-plate and other parts of the device in this modified form are the same as hereinbefore referred to in connection with the other figures of the drawings, the same reference-numerals being applied thereto.

The independent air-passage 23 is provided to obtain the thorough incandescence of the 85 mantle and greater heat in the heater by the employment of a smaller quantity of gas than employed in the ordinary burners. It will also prevent the accumulation of carbon upon the mantle, for the reason that the operator 90 cannot when regulating the burner shut off the air, or if the air-inlets at the bottom of the mixing-tube should be clogged in any way the independent air-passage 23 will supply air to the burner. It will be evident that by 95 constructing the burner-tube and mixing-tube with the air-passages, as shown, the ordinary air-shutter used in devices of this character can be dispensed with. It will also be evident that owing to the arrangement of the 100 plate 10 the supply of gas can be regulated at will from the gas-supply pipe to the burner. By the employment of the construction of mixing-tube as shown in connection with the burner-tube the air can be mixed with the incoming gas more than once before the latter is ignited, not only through the air-inlets 8, but also through the passages 18, and as the air approaches the heat it will more intimately unite with the gas when brought together, 110 and it is thought that the many advantages of an incandescent burner constructed in accordance with this specification, taken in connection with the accompanying drawings, can be readily understood, and it will be noted 115 that minor changes may be made in the details of construction without departing from the general spirit of my invention.

Having thus described my invention, what I claim as new, and desire to secure by Letters 120 Patent, is—

1. In an incandescent gas-burner, the combination with a mantle and a burner-tube provided with air-inlets, of a mixing-tube having a portion thereof surrounding said burner-tube and provided with an enlarged portion arranged above the burner-tube forming a gas and air mixing chamber, said lower portion of the mixing-tube forming air-passages 130 between the same and the burner-tube and further provided with air-inlets, and a cap mounted upon the enlarged portion of the mixing-tube and adapted to form independent air-passages between the said enlarged

- portion and the inner face of the side walls of the cap.
2. In an incandescent gas-burner, the combination with a mantle and a burner-tube provided with air-inlets, of a mixing-tube having a portion thereof surrounding said burner-tube and provided with an enlarged portion arranged above the burner-tube forming a gas and air mixing chamber, said lower portion of the mixing-tube forming air-passages between the same and the burner-tube and further provided with air-inlets, a cap mounted upon the enlarged portion of the mixing-tube and adapted to form independent air-passages between the said enlarged portion and the inner face of the side walls of the cap, and means arranged in the burner-tube and operated by the mixing-tube for regulating the supply of gas.
3. In an incandescent gas-burner, a mixing-tube constructed of an upper and lower portion of different diameters, the smaller of which is provided with a vertical groove at the bottom and the larger of which forms a gas and air mixing chamber, and a cap mounted upon the said larger portion of said mixing-tube and adapted to form an air-passage between the same and said larger portion.
4. In an incandescent gas-burner, the combination with a burner-tube connected to a gas-supply and provided with air-inlets, of a means arranged in the said tube for regulating the supply of gas thereto, a mixing-tube surrounding the said burner-tube and having its upper portion forming a mixing-chamber and its lower portion adapted to engage said regulating means for operating it, and a cap mounted upon the upper portion of the mixing-tube and adapted to form an air-passage between the mixing-tube and the wall thereof.
5. In an incandescent gas-burner, the combination of a nipple connected to a gas-supply and provided with a peripheral flange and a shoulder, a burner-tube mounted upon said shoulder and provided with air-inlets, a rotatable mixing-tube mounted upon said flange, surrounding said burner, provided with air-inlets and forming air-passages between the burner and inner face of said mixing-tube, said mixing-tube forming in its upper portion the gas and air mixing chamber, a cap mounted upon the upper portion of the mixing-tube to form an air-passage, and means arranged in the burner-tube and operated by the mixing-tube for regulating the supply of gas to the burner.
6. In an incandescent gas-burner, a burner-tube, a rotatable mixing-tube surrounding said burner-tube and forming air-passages between the same and the inner face of said mixing-tube, and a plate arranged in the burner-tube and operated by the mixing-tube for regulating the supply of gas.
7. In an incandescent gas-burner, the combination with a burner-tube connected to a gas-supply, of a rotatable mixing-tube surrounding the same and having its upper portion terminating in a gas and air mixing chamber and its lower portion formed with an offset, a plate arranged in the burner-tube and adapted to regulate the supply of gas and a stud integral with the plate and engaging in the offset of the mixing-tube to cause the operation of the plate when the said mixing-tube is rotated.
8. In an incandescent gas-burner, the combination with a burner-tube provided with beads, of a rotatable mixing-tube surrounding the burner-tube and engaging the beads for retaining it in a uniform position, air-passages formed between the burner-tube and the mixing-tube, air-inlets provided in the mixing-tube, a plate arranged in the burner-tube for regulating the supply of gas, and means carried by the plate and engaged by the mixing-tube for causing the operation of the plate when the mixing-tube is rotated.
9. In an incandescent gas-burner, a nipple connected to a gas-supply and provided with an annular shoulder and a peripheral flange, a perforated diaphragm connected to the top of the nipple, a burner-tube connected to the nipple and engaging the shoulder thereon, said burner-tube provided with a slot, air-inlets above the said slot and a plurality of beads, a rotatable mixing-tube surrounding the burner-tube and mounted upon the flange of the nipple, said mixing-tube provided with air-inlets and an offset, a plate mounted upon the diaphragm and adapted to regulate the supply of gas therethrough, and a stud integral with the plate extending through the slot of the burner-tube into the offset of the mixing-tube and adapted to cause the operation of said plate when the mixing-tube is rotated.

In testimony whereof I have hereunto set my hand in presence of two subscribing witnesses.

CLARENCE W. TAYLOR.
